INVENTOR

HENRY T. BUSSMANN,

by

Spelman ATTORNEY.

UNITED STATES PATENT OFFICE.

HENRY T. BUSSMANN, OF ST. LOUIS, MISSOURI.

ELECTRIC FUSE.

Application filed May 7, 1919. Serial No. 295,372.

To all whom it may concern:

Be it known that I, HENRY T. BUSSMANN, a citizen of the United States, residing at St. Louis, Missouri, have invented a certain new and useful Electric Fuse, of which the following is a full, clear, and exact description, such as will enable others skilled in the art to make and use the same.

My invention relates to electric fuses and 10 refers particularly to that type known as the refillable knife blade cartridge type; yet I do not limit my invention to this type as certain of my improvements are likewise desirable in other types of fuses.

15 The object of my invention is to provide a fuse that can be easily and quickly renewed. This and other advantages of my invention will be more readily understood by reference to the accompanying drawings, 20 which show a preferred embodiment of my invention. In describing the device shown in the drawings hereto attached and described in the specifications, I do not limit my invention to the precise form, shape or 25 construction of the fuse shown, or to the several parts thereof, as various alterations can be made without changing the scope of my invention.

Fig. 1 is a view of my fuse, having a section broken out to show the arrangement thereof. Fig. 2 is a similar view, 90 degrees removed from the position shown in Fig. 1. Fig. 3 shows a preferred form of my terminal holding device. Fig. 4 shows an alternate construction.

In the drawings, 6 is a casing, of fiber or other suitable material. 7 is a member, which is preferably provided with threads 10 or other means for removably holding the 40 cap 9. This member is held by threads 8 or any other suitable means and is held against rotation by rivets 11. It is preferably fitted inside the casing, so that when the fiber shrinks, it serves to hold the member firmly, 45 although it is obvious that I may attach this member outside the casing as shown in Fig. 4.

The flat blade terminals 12 are removably connected to the fuse link 13 by bolts 14, or 50 other suitable means.

The inner periphery of the member 7 is so

shaped as to hold the terminal 12 against rotational movement. While any non-circular interior of proper dimensions will so hold the terminal, I prefer to use grooves as 55 shown at 15. One of these members being placed at each end of the casing, with the grooves properly positioned, the terminals 12 are held in the same plane and in substantial alignment with each other.

To hold the terminals against longitudinal movement, I provide a terminal holding device, which consists preferably of two parts 16. These parts are pressed against and firmly hold the terminals 12 by reason of their tapered outer periphery 17 and the tapered walls 18 of the cap 9. These parts are seated on the member 7 and when held in position by the cap attached to the member, their holding power cannot be affected 70 by any shrinkage in the length of the casing. Such shrinkage would, if the parts were seated directly on the fiber casing, permit them to become loose and release their hold on the terminals. It is obvious that these 75 parts may be reversed on the member and the inner periphery of the member, arranged to hold them, in which event the cap may be made with straight walls as shown in Fig. 4.

When the fuse is inserted into the jaws of 80 a fuse block, edgewise movement of the terminal occurs. Such edgewise movement, if permitted, injures the fuse link or loosens its fastening, resulting in premature burn-out of the fuse link. To prevent this edgewise movement, I provide the parts with 85 projections 19, so as to entirely surround the terminal and I make these parts of substantial thickness, thereby providing bearing points 20, 20' and 21, 21' separated from 90 each other and in constant spaced relation to each other. These projections 19 also serve to entirely close the case.

To prevent the escape of flame or gases on the blowing of the fuse, I prefer to arrange 95 that all of the openings in the assembled fuse have indirect angular paths, so that such flame or gas must pass through such indirect paths and is, therefore, substantially restricted from escaping from the fuse. For 100 this reason I provide a portion of the terminal near the end of the casing with an in-

terrupted surface 22 extending completely around the terminal. I also provide such interrupted surface on the projections 19 of the washers 16 where they abut each other 5 and preferably also on that portion of the washers in contact with the terminals in which event such interrupted surface is made to coincide with the interrupted surface of the terminal.

10 Such interrupted surface may be grilled, corrugated, channeled, or made uneven in any manner that would provide a restricted exit for flame or gas.

15 It can be readily seen that this interrupted surface also serves to hold the terminal more firmly against longitudinal movement.

20 Due to the clearances necessary between the bolts 14 and the holes in the terminal and fuse link through which they pass, a variation in length of the assembled element occurs. The shrinkage of fiber also causes variations in the length of the casing. To overcome these variations I make the interrupted surface on the terminal substantially 25 wider than the thickness of the parts so that the parts will always engage an interrupted surface notwithstanding limited variations in the relative length of the fusible element and casing. It is obvious that where these 30 variations are prevented or where other means are employed for taking care of these variations, that this interrupted surface need be approximately only as wide as the thickness of the parts.

35 What I claim is:

1. In an enclosed knife blade fuse, a casing, a flat blade terminal, a member permanently attached to the casing and adapted to prevent the rotation of the terminal and 40 means seated on said member for wedging the terminal and holding it against longitudinal movement.

2. In an enclosed knife blade fuse, a casing, a member permanently attached to the 45 casing adapted to hold a flat blade terminal in a predetermined position against rotation, a flat blade terminal extending within the casing, a tapered holding device seated on said member for holding the terminal 50 against longitudinal movement, and a cap removably fitted to said member for holding said tapered device tightly against said member.

3. In an enclosed knife blade fuse, a casing, a terminal, a member permanently attached to the casing, preventing rotational movement of the terminal, a tapered holding device seated on said member, a cap removably fitted to said member and means 60 in the cap for causing the tapered holding device to press against the terminal to hold said terminal against longitudinal movement.

65 4. In an enclosed knife blade fuse, a casing, a terminal, a member permanently at-

tached to the casing, preventing rotation of the terminal and a tapered device for restraining the longitudinal movement of the terminal and a cap adapted to bear on the tapered device.

70 5. In an enclosed knife blade fuse, a casing, a cap, a terminal extending within the casing, a tapered terminal holding device, said device having bearing points substantially separated and in constant spaced relation to each other, whereby the edgewise movement of the terminal relative to the casing is substantially prevented, the holding device being wedged against the terminal to prevent the longitudinal movement of the terminal.

75 6. In an enclosed knife blade fuse, a casing, a flat-blade terminal extending within the casing, a split tapered holding device for wedging and positioning the terminal against longitudinal movement, said device completely surrounding the terminal and closing the casing.

80 7. In an enclosed fuse, a casing, a terminal, a tapered terminal holding device adapted to be wedged against the terminal and having an interrupted surface on the edges abutting the terminal, to provide an indirect exit for gas when the fuse is blown.

85 8. In an enclosed fuse, a casing, a terminal having a portion thereof with an interrupted surface substantially about its periphery, a terminal holding device adapted to be wedged against said portion of the terminal and providing an indirect exit for gas when the fuse is blown.

90 9. In an enclosed fuse, a casing, a terminal, a tapered terminal holding device consisting of a plurality of parts surrounding the terminal and having interrupted surfaces on the abutting edges of such parts, providing an indirect exit for gas when the fuse is blown.

95 10. In an enclosed fuse, a casing, a terminal, a tapered terminal holding device, surrounding the terminal, said terminal and device having interrupted surfaces abutting each other to provide an indirect exit for gas when the fuse is blown.

100 11. In an enclosed fuse, a casing, a terminal, a tapered terminal holding device surrounding the terminal, said terminal having an interrupted surface of greater width than the thickness of the holding device.

115 12. In an enclosed fuse two members each having a substantially flat face adapted to be placed in abutting relation with the face of the other member; a portion of one of said faces being interrupted to provide indirect passageways between said faces for the exit of gases on the blowing of the fuse.

120 13. In an enclosed fuse, a plurality of members in abutting relation, one of said members having a portion of its abutting surface knurled, to provide a plurality of

indirect channels between said abutting members for the exit of gases produced on the blowing of the fuse.

14. In an enclosed fuse, a plurality of members in abutting relation one of said members having variations in a portion of its abutting surface whereby indirect passageways with a plurality of baffles therein are provided between the abutting members,

to allow of the exit of gases therethrough on the blowing of the fuse.

15. In an enclosed fuse two members in abutting relation and means on the members for holding of them against relative displacement and providing a plurality of indirect passages between the members for the exit of gases on the blowing of the fuse.

HENRY T. BUSSMANN.
